US0D1022756S

(12) United States Design Patent (10) Patent No.: US D1,022,756 S
(45) Date of Patent:  *Apr. 16, 2024

(54) BAND

(71) Applicant: Apple Inc., Cupertino, CA (US)

(72) Inventors: Jody Akana, San Francisco, CA (US); Molly Anderson, San Francisco, CA (US); Bartley K. Andre, Palo Alto, CA (US); Shota Aoyagi, San Francisco, CA (US); Anthony Michael Ashcroft, San Francisco, CA (US); Marine C. Bataille, San Francisco, CA (US); Jeremy Bataillou, San Francisco, CA (US); Markus Diebel, San Francisco, CA (US); M. Evans Hankey, San Francisco, CA (US); Julian Hoenig, San Francisco, CA (US); Richard P. Howarth, San Francisco, CA (US); Jonathan P. Ive, San Francisco, CA (US); Julian Jaede, San Francisco, CA (US); Duncan Robert Kerr, San Francisco, CA (US); Marc A. Newson, London (GB); Peter Russell-Clarke, San Francisco, CA (US); Benjamin Andrew Shaffer, San Jose, CA (US); Joe Sung-Ho Tan, Vienna (AT); Clement Tissandier, San Francisco, CA (US); Eugene Antony Whang, San Francisco, CA (US); Rico Zörkendorfer, San Francisco, CA (US)

(73) Assignee: Apple Inc., Cupertino, CA (US)

(*) Notice: This patent is subject to a terminal disclaimer.

() Term: 15 Years

(21) Appl. No.: 29/833,145

(22) Filed: Apr. 1, 2022

Related U.S. Application Data

(63) Continuation of application No. 29/746,615, filed on Aug. 14, 2020, now Pat. No. Des. 949,039.

(57) CLAIM

The ornamental design for a band, as shown and described.

DESCRIPTION

FIG. 1 is a bottom front perspective view of a band showing the claimed design;

FIG. 2 is a bottom rear perspective view thereof;

FIG. 3 is a front view thereof;

FIG. 4 is a rear view thereof;

FIG. 5 is a left side view thereof;
 FIG. 6 is a right side view thereof;
 FIG. 7 is a top view thereof;
 FIG. 8 is a bottom view thereof; and,
 FIG. 9 is a perspective view thereof showing the band in a state of use.
 The broken lines in FIGS. 1-8 represent portions of the band and form no part of the claimed design. The other broken lines in FIG. 9 represent environmental subject matter only and form no part of the claimed design.

1 Claim, 5 Drawing Sheets
